UNITED STATES PATENT OFFICE.

EDWARD KEMYES CORNELL, OF NEW BEDFORD, MASSACHUSETTS.

SCOURING IMPLEMENT.

Application filed March 8, 1924. Serial No. 697,859.

To all whom it may concern:

Be it known that EDWARD K. CORNELL, a citizen of the United States, residing at 88 Elm Street, New Bedford, in the county 5 of Bristol and State of Massachusetts, has invented certain new and useful Improvements in Scouring Implements, of which the following is a specification, reference being had therein to the accompanying drawing.

10 This invention relates to scouring devices for use in connection with kitchen and table utensils, but includes certain features capable of wider application.

15 The principal purpose of the invention is to provide a scouring device of the type mentioned, consisting of a filler block loosely enclosed in a special fabric envelope and equipped with a handle to provide for manipulation of the block and fabric in the use 20 of the device.

A further purpose of the invention is to provide an improved form of scouring fabric consisting of a series of metal rings having flat sides and edges and interlocked to provide 25 an envelope which may be used alone or in connection with the filler block and handle previously mentioned.

Other purposes and advantages of the invention, as well as the details of construction, 30 and arrangement of parts disclosed herein, will be more fully understood from the following detailed description and accompanying drawings, in which—

35 Fig. 1 is a perspective view of a filler block and handle constructed in accordance with my invention.

Fig. 2 is a fragmentary perspective view 40 of the filler block and handle showing the manner of attaching the scouring fabric thereto.

Fig. 3 is a fragmentary view of the scouring fabric showing the manner in which the metal rings are interlocked.

Fig. 4 is a perspective view of one of the 45 metal rings; and

Figs. 5 and 6 are perspective views illustrating the use of the device in connection with different types of utensils.

50 Referring more particularly to the drawings, 5 designates a handle member which is enlarged at one end to provide a filler block 6. This filler block is enclosed at all

sides within a scouring fabric or envelope 7 composed of a plurality of metal rings 8 interlocked as shown in Fig. 3, and individually shaped as shown in Fig. 4. In assembling the device the fabric envelope 7 is slipped over the filler block 6 and the mouth of the envelope is then contacted around the handle member 5 and secured thereto by wire 9 or equivalent means.

As shown in Fig. 2, the envelope 7 is considerably larger than the filler block 6 so that the latter is capable of limited movement within the envelope. In practice, it 65 has been found that this limited movement of the filler block within the envelope during manipulation of the handle member 5 gives a better scouring action than would be the case if the envelope were a tight fit on the 70 filler block.

If desired, the envelope 7 may, upon removal of the fastening wire 9, be detached from the filler block 6 and used alone in the manner of a dish cloth.

75 While in the foregoing, I have described what I now consider to be the preferred embodiment of my invention, it will be understood that various changes may be resorted to within the scope and spirit of 80 the appended claims.

What I claim is:

1. A scouring implement for kitchen utensils comprising a filler block, a handle carrying said block and a metal scouring fabric 85 in the form of an envelope composed of a plurality of interlocked rings enclosing said block, said block and handle constituting a pressure applying and manipulating means for the scouring fabric.

90 2. A structure according to claim 1 in which the envelope is made larger than the block to permit limited movement of the latter therein.

3. A scouring implement for kitchen 95 utensils comprising a scouring fabric consisting of a series of metal rings having flat sides and edges and interlocked to form an envelope having an entrance or opening, a pressure applying and manipulating block 100 contained within said envelope, an elongated handle attached to said block and means securing the mouth of the envelope around said handle.

4. A scouring implement for kitchen utensils comprising a pressure applying and manipulating block, a handle member carrying said block, a metal scouring fabric in the form of an envelope loosely enclosing said block at all sides of the latter and made slightly larger than the block to permit the

latter to have a limited movement therein, and fastening means restricting and securing the mouth of the envelope to the handle.

In testimony whereof I hereunto affix my signature.

10

EDWARD KEMYES CORNELL.
